REMOVABLE RECEPTACLE FOR FLOOR SWEEPINGS

Donald C. Hultquist, 8212 Penn Ave. S., and Donald G. Franzen, 11408 Goodrich Road, both of Bloomington, Minn.

Filed Oct. 7, 1963, Ser. No. 76,893

Term of patent 14 years

(Cl. D58—17)

FIG. 1

FIG. 2

FIG. 3

FIG. 1 is a view in perspective of a removable receptacle for floor sweepings showing the front, top and one end of our new design;

FIG. 2 is an inverted perspective view thereof; and

FIG. 3 is an enlarged view in section thereof taken on the line 3—3 of FIG. 1.

We claim:

The ornamental design for a removable receptacle for floor sweepings, as shown.
